(57) **CLAIM**

The ornamental design for a bone staple inserter as shown and described.

DESCRIPTION

FIG. 1 is a top front perspective view of a bone staple inserter having a handle and a grabber in a first position showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a top view thereof, showing the handle and grabber in a second position of use.

The broken lines shown in the figures illustrate portions of the bone staple inserter that form no part of the claimed design.

1 Claim, 8 Drawing Sheets
